UNITED STATES PATENT OFFICE

HELMUTH REINHARDT ROSENBAUM, OF MADRID, SPAIN

RAILROAD

Application filed November 6, 1926, Serial No. 146,713, and in Germany August 10, 1925.

The object of my invention is to improve upon railroad tracks as they are in use today, and thereby benefit greatly railroading in general. My efforts were directed towards 5 eliminating jars and joints of the rails in use at the present time and have led me to the discovery that this may be achieved by employing compound rails, that is to say rails of certain smaller sections which when assembled produce a compound rail of approximately the section of the single compact rails used at present. The tracks are then built in such a way that never more than one of the rails making up the compound starts anew, 10 at a time. The accompanying drawing shows the invention.

If, for instance, in a rail made up of four parts the third one starts anew, the sections Numbers 1, 2, and 4 continue, and so on, in 15 such a way that the train runs on endless rails, practically speaking, and the jars and joints as of the solid rails now in use have disappeared completely.

I claim as my invention:

20 1. In a compound rail, a vertical, longitudinally subdivided, downwardly laterally outwardly flaring and upwardly laterally thickened intermediate section, and complementary lateral rail sections engaging said intermediate sections at the sides thereof.

25 2. In a compound rail an intermediate, longitudinally extending and longitudinally subdivided, vertical, cross-sectionally laterally broadened interior rail-section, and complementary lateral rail-sections closely engaging 30 with the entire side-surfaces of said interior section, and flush with the upper surface of said interior section.

30 3. In a compound rail, an intermediate, longitudinally subdivided, upright, rail section, comprising an outwardly flaring bottom portion, and complementary lateral rail sections engaging the intermediate section and of substantially equal height therewith.

35 4. In a compound rail, an upright, inter-

mediate section, comprising an outwardly bevelled thickened supporting base portion, and complementary lateral sections, engaging the entire side-surface of the intermediate section, and flush with the tread surface thereof.

50 In testimony whereof I affix my signature.

HELMUTH REINHARDT ROSENBAUM.
